TAG FASTENER

Nathan I. Fleischer and Roy Holle, Cincinnati,
Ohio, assignors to The Fleischer Mills, Inc., Cincinnati, Ohio, a corporation of Ohio

Application December 29, 1948, Serial No. 67,866

2 Claims. (Cl. 40—22)

1

This invention relates to tag fasteners, and more particularly to tag fasteners of the type used by the laundry and dry cleaning industries for securing identification media to garments and other items to be dry cleaned, laundered, or otherwise serviced.

An object of the present invention is to provide a reenforced tag fastener which is constructed in such a manner as to facilitate positive attachment to an item, in response to a simple squeezing operation on the part of an operator.

A further object of the invention is to provide a tag fastener including a combination piercing and locking tongue adapted to readily pierce those items to which the tag is to be attached, and wherein the free end of said piercing tongue will be automatically and securely locked to another portion of the fastener, incident to a squeezing operation, whereby the locking tongue will be turned upwardly thereby positively anchoring said tongue against accidental or unintentional disengagement from that portion of the fastener with which it is engaged, for effectively precluding accidental or unintentional disengagement or removal of said fastener from the item to which it is attached, incident to rough or unusual handling to which it may be subjected.

Another object of the invention is to provide a tag fastener including a piercing-tongue-engaging-portion which is constructed and arranged in such a manner as to insure positive locking engagement with portions of a piercing tongue inserted therein, and wherein said locking action is emphasized or augmented incident to the application of an outward pull on a tag secured to an item by the fastener. In those prior art devices with which we are familiar the locking action of the piercing tongue elements is seriously impaired and often rendered ineffective by an endwise pull on the identification tag secured to an item by a fastener; such an endwise pull tending to withdraw or unseat the tongue element from its locked position.

Another object of the invention is to provide an improved tag fastener wherein an identification tag is positively secured to the fastener, being located intermediate the legs thereof.

Still another object of the invention is to provide a tag fastener one leg of which comprises a single thickness of material, the other leg of which comprises a double thickness of material.

2

Still a further object of the invention is to provide a tag fastener having the hereinabove mentioned characteristics which may be detached or removed from a garment in response to a deliberate action on the part of an operator.

A further object of the invention is to provide a tag fastener having the hereinabove described characteristics which may be inexpensively fabricated using modern mass production methods.

These and other objects are attained by the means described herein and as disclosed in the accompanying drawings, in which:

Fig. 1 is a plan view of a length of strip material formed in accordance with the teachings of the present invention and ready to be bent to provide a tag fastener.

Fig. 2 is a side view, partly in section, of a tag fastener fabricated from the blank of Fig. 1, showing the fastener in a ready-to-attach condition.

Fig. 3 is a vertical section of the fastener of Fig. 2 secured to an item in an attached, fully closed or locked position.

With reference to Fig. 1 the numeral 10 denotes generally a length of strip sheet material provided with a combination piercing and locking tongue 12 and a tag attachment wing 14, struck therefrom, said tongue and wing being provided in leg 16, which may, if desired, be set off from the strip by means of a score mark 18. Those portions of the strip remote from leg 16 are provided with a lateral offset 20, and an aperture 22, as illustrated.

The blank of Fig. 1 may be formed whereby to comprise a single leg and a double leg, said double leg being formed by bending inwardly about axis 24, those portions of leg 26 located beyond lateral offset 20 and axis 24 into a position in overlapping relationship with the concave side of said offset in leg 28 for providing a fastener leg having a double thickness.

The single and double leg of the fastener may be bent on an axis passing thru score or fold line 18 for providing the V-shaped fastener illustrated in Fig. 2, it being understood that a suitable identifying tag 30 may be disposed on and permanently secured to the inner face of leg 16 by means of wing 14 which may, as clearly disclosed in Figs. 2 and 3, be folded or crimped downwardly over the upper edge of a tag 30.

As disclosed in Fig. 2 a tongue receptive pocket 32 is formed when inner leg 26 has been folded over offset 20, it being further observed that aperture 22 is located adjacent and overlying

offset portion 20 for controlling access to pocket 32.

With reference now to Fig. 3 it will be observed that the fastener may be secured to an item denoted generally by the numeral 40 by the application of a squeezing force for the purpose of bringing the single and double legs together, whereby tongue 12 will first pierce thru item 40 and then pass into and thru aperture 22, thence into pocket 32. As the tongue is thus introduced into pocket 32, its forward edge will engage offset portion 20 which will deflect the free end of tongue 12 upwardly, away from the juncture 46 of the single and double legs of the fastener, for disposing said tongue in the relative position illustrated in Fig. 3.

It will be observed that a downward pull on tag 30, in a direction indicated by the headed arrow 41, will augment the locking relationship of tongue 12 with aperture 22 and pocket 32, thereby effectively precluding removal or withdrawal of the tongue from said pocket. This feature is of particular importance from a practical standpoint since identification tags are quite frequently accidentally or unintentionally detached from the items to which they have been secured by reason of an endwise pull on the identifying tag; such unintentional removal occurring in the prior art devices by reason of the fact that the locking tongues are turned downwardly, that is, toward the juncture between the legs, whereby the application of a downward force on the identifying, indicia bearing tag will result in a withdrawal of the locking tongue. Our fastener completely obviates such accidental or unintentional disengagement of a fastener from an item to which it has been secured.

Although our fastener will effectively resist removal by reason of an endwise pull directed thereto, such as, thru identification tag 30, the fastener may, nevertheless be quickly and effectively detached from the item to which it has been locked incident to the application of a separating force applied to the upper ends 42 and 44 of the legs. The application of such a deliberate force will effect a withdrawal of tongue 12 thru aperture 22 incident to which withdrawal operation tongue 12 will be effectively straightened, thereby eliminating possibility of said tongue from tearing, snagging or otherwise injuring item 40 impaled thereon.

With particular reference now to Figs. 2 and 3, it will be observed that the inner panel or leg 26 of the so-called double leg effectively reinforces the other panel or leg 28 in such a manner as to preclude bending thereof incident to normal manipulation of the device.

The double leg likewise effectively and efficiently precludes the occurrence of an undesired separation of the legs incident to an endwise pull, such as indicated by the headed arrow 41, Fig. 3, since element 26, by reason of its coplanar relationship with element 28 resists the otherwise distorting effects transmitted to said element via tongue 12 passing through aperture 22.

It will be observed that when the fastener has been closed or locked, the inner face of element 26 contacts wing 14 thereby presenting a solid, non distortable relationship of parts which will securely hold element 26 against and in coplanar relationship with the outer leg or element 28 incident to withdrawal of tongue 12 from pocket 32 via aperture 22.

What is claimed is:

1. A tag fastener comprising a narrow strip of metal bent into substantially equal portions forming two legs, one leg having a piercing and locking tongue struck up therefrom, the other leg having an offset in the body thereof adjacent the free end, an extension of the second leg being bent inwardly and over the second leg forming with the offset a receiving pocket having an opening communicating therewith and with the opening overlying said offset, said opening adapted to receive the piercing and locking tongue when the two legs are brought toward each other, the offset being so shaped as to form an anvil which when engaged by the piercing and locking tongue extending through the opening will force the same outwardly in the receiving pocket toward the free end of the leg so that any pull on a tag held in the bend in a direction away from the free ends of the strip will prevent disengagement of the locking tongue from the receiving pocket.
2. A tag fastener comprising a single strip of narrow metal bent into three substantially equal parts with one of the ends bent inwardly and over the center portion of the strip, the free end having two struck up tangs thereon, the tang nearest the bend adapted to retain a tag placed on the fastener, an offset adjacent one end of the central portion, the bent over end having an opening therein overlying the offset when that end is folded over the center portion the opening adapted to receive the second tang adjacent the free end of the strip, the offset being so shaped as to form an anvil which when engaged by the tang will force the same outwardly and into a receiving pocket formed by the offset and the bent over end so that any pull on the tag in a direction away from the bend between the free end and center portion will prevent disengagement of the tang from the receiving pocket.
